INTERNAL COMBUSTION ENGINE

Hjalmar Zahl, Duluth, Minn.

Application November 12, 1938, Serial No. 240,033

5 Claims. (Cl. 123—8)

This invention relates to internal combustion engines, but to a type differing from those commonly known as reciprocating or rotary engines, and which it is deemed may be properly termed a 5 rotor and endless piston rod engine.

The principal object is to provide a more efficient power unit of the internal combustion engine type.

Another object is to provide such a power unit 10 having the maximum piston travel in relation to the power developed.

Other objects and advantages of the invention will appear in the following description thereof.

Referring now to the accompanying drawings, 15 forming part of this application, and wherein like reference characters indicate like parts:

Figure 1 is a reduced elevation, partly in section, showing the general arrangement of the principal parts of one of the engines.

Figure 2 is an enlarged elevation, partly in section, of slightly more than one-half of the completely assembled engine, and having the near side member of the engine frame removed.

Figure 3 is an under side plan view of that 25 portion shown in Figure 2, with parts thereof in section.

Figure 4 is an enlarged transverse section of one of the power or compression pistons.

Figures 5 and 6 are sections on their respective 30 lines 5—5, and 6—6, as indicated on Fig. 2, the former illustrating particularly water cooling means about the head of the power cylinder, if such is found necessary.

Figure 7 is a transverse section of one of the 35 supporting channels 1 adjacent one of the timing rollers 46 and showing the oscillatory support thereof.

Figure 8 is a section through the housing on the line 8—8, Fig. 2, illustrating possible water 40 cooling conduits and showing the quadrants and their supporting shafts in elevation.

In the drawings, 1—1 represent the side members of a supporting frame for the engine, within 45 which are supported two spaced non-rotatable shafts 2 and 3, the latter having means for lateral adjustment, the need for which will be described later.

Upon these shafts are rotatably mounted relatively narrow drum-like rotors 4 and 5, respectively, they having flat peripheral surfaces and arranged with spaced flanges for carrying two flat metal bands, one considerably wider than the other, the former being for the reception of the endless band 6 and the other for the carrying 55 of the narrower band 7. These bands are for the carrying

of pistons, the wider one carrying a plurality of engine or power pistons 8, while the narrower one carries a like number of compression pistons 9. The rotors are provided with notches indicated at 10, both for the large and small pistons 5 for receiving same, said notches being spaced the proper distance apart around the periphery of the rotors to register properly with the pistons as they traverse the rotors so that they form a means for positive relative movement of the rotors and bands.

Intermediate of the rotors 4 and 5 and fixed to the side frames 1 as by brackets indicated at 11 is a combined air chamber and somewhat Z-shaped housing structure and support, indicated 15 at 12, and within either extremity of said housing is incorporated a pair of cylinders, the one indicated at 13 on either side being the power cylinder and the one indicated at 14 being the compression cylinder. These cylinders are so positioned upon either side of the structure that the band 6 carrying the power pistons registers with the cylinders 13 axially and so traverses same, while the compression pistons 9, carried upon the belt 7, similarly traverse the compression cylinders 14. 20

Each of the power cylinders is provided with means for opening and closing same at the proper predetermined time in respect to the travel of the pistons 8, while the compression cylinders are 30 similarly equipped at the opposite ends for such cooperation with their respective pistons.

For the operation of such opening and closing mechanism, at the receiving end of each cylinder 13 and outwardly of same is installed quadrant and toggle mechanism, the quadrants being shown at 15 and 16 while two of the levers are shown at 17 and 18 for the manipulation of the pivotally mounted lips or jaws 19 of the closure or gate for each cylinder after the passage of a 40 piston 8 therethrough, while at the opposite or discharge end of each compression cylinder a like pair of gate jaws 20 are shown, they each being pivotally mounted as at 21 to a suitable lateral extension of the cylinder and controlled 45 as by the toggle levers 22 pivotally united as at 23 and operated by the extension levers 24 connecting with suitable levers keyed to the pivotal shafts 25 upon which the quadrants 15 and 16 at the receiving end of the power cylinders are 50 mounted, so that as the receiving end of the power cylinder is closed the discharge end of the compression cylinder will also be closed, or the reverse, as the case may be. It is obvious from the drawings that the jaws 19 of the power cylin- 55

der are pivoted as at 26 and operated by the other extremity of the toggle levers 17 and 18 as at O, pivotally attached to their respective quadrants as at 27 and 28.

5 This quadrant and toggle arrangement for the opening and closing of the two cylinders upon either side of the engine is accomplished as by a short lever 29, pivotally connected as at 30 to the short arm of the quadrant 16, and its opposite 10 end is pivotally connected as at 31 to the lever arm 32 as well as the pivotally supported sustaining rod 33 being somewhat spring controlled or governed as by the expansive helical spring 34 on said rod and tending to normally hold the 15 rod towards closed position of the gates 19. The lever 32 is pivoted as at 35 and connected intermediate of its ends as at 36 to the adjustably operated connection including the arm 37 and inverted T-shaped lever 38 pivotally and rockably 20 mounted upon a suitable bracket 101 fixed to one side member 1 of the engine frame and at the extremity of the stem portion of the T-shaped lever is the pivotal connection 39 for the rotor engaging arm 40, providing the necessary make 25 and break contact, as at 41, to the spark plug 52. It will be noted that the adjustment feature intermediate of arm 37 and lever 38 is readily accomplished as by the attachment of the clip 42 to the lever 38 carrying the screw threaded adjusting bolt 43 held within the offset portion 44 of the arm 37.

30 In the matter of proper timing of the operation of the lever 38 I have provided the track 45 upon each of the rotors for the roller 46 carried in the rotor end of the lever 38 and this track is formed with outwardly jogged diametrically opposed channel portions indicated at 47 wherein when the roller 46 enters such jog in the track the lever 38 is thrust outwardly to correspondingly 40 move the lever 32 on its pivotal support 35, and these jogged portions of the track are positioned in proper relation to the recesses 10 in the rotors for the pistons 8 so that they will close the gates or mouth of the cylinder the desired predetermined time after the piston 8 has entered each 45 cylinder where it is ready for the compressed fuel charge to be received through the port 48. This port is at the terminus of the pipe 50 leading from the reservoir 51 and is controlled by any form of 50 rotary valve indicated at 49, the operation of which will be described later.

55 It will be noted that the jogged channel portions of the track 45 are somewhat elongated for the purpose of retaining the roller 46 momentarily in such channel portion before contacting the exit terminal of such jog, this being for the purpose of allowing the pistons 8 to enter a predetermined distance within their respective cylinders to provide the necessary time and the otherwise 60 unoccupied portion of each cylinder to become free for the insertion of the explosive charge. The communication from the compression cylinder 14 to the engine cylinder for admission of the charge back of the piston after its entrance into the cylinder is controlled by a toggle arrangement of 65 levers pivotally mounted upon the pivot 39 on the stem portion of the T-shaped lever 38, and while it might appear essential that this pivotal point be stationary yet such is not the case as such 70 pivotal point has slight movement to and from the rotor adjacent same, the functioning of which brings about proper relation of the actuating ends of the levers so mounted, and the functioning of the lever 40 having been previously described. Together with this lever 40 are mount-

ed the levers 53 and 54 which have a toggle connection with the angularly shaped crank arm 55 through the arms 56 which open and close the valve 49.

5 The functioning of this toggle arrangement of levers from the T-shaped lever 38 is brought about by a pair of dogs 57 carried upon the side of each rotor adjacent the recesses 10 within same, so that when the dog adjacent the uppermost recess 10 engages the actuating end of the 10 lever 54 as it is brought into the path of the dog by the end of the lever 38 being drawn inwardly towards the rotor as it passes out of the jogged channel 47, it will open the valve 49 admitting the compressed charge into the cylinder, which operation brings the actuating end of the lever 53 into the path of the dog 57 which, when struck by the continued rotation of the rotor, will close the valve 49 again, and a still further fractional continuation of the rotor will 20 bring the dog 57 into contact with the actuating end of the lever 40, closing the contact 41 to the spark plug 52 and firing same, this obviously being a very simple progressive actuation of this 25 toggle connection of levers.

30 While there has been described the operation of one set of levers as associated with one pair of cylinders, it is obvious that the identical arrangement must be duplicated for the other pair of cylinders, and practically the only part of the 35 mechanism common to both, other than the bands and rotors and their respective parts, is the compression chamber and its associate parts. This part of the engine is better illustrated in Figure 3 of the drawings where a plan view of 35 same is shown as installed intermediate of the rotors and attached to the side members 1—1 of the supporting frame of the engine.

40 It will be noted that the brackets 11 which support the housing 12 are materially enlarged laterally with the one on one side of the housing being hollow and forming the main air reservoir, and which has formerly been referred to as 51, see Fig. 1, while the bracket on the other side is similarly chambered as indicated 45 at 60, and in which is fixed a stationary rod like member 61 having a plurality of annuli 62 thereupon simply to form a tortuous route for the compressed air after receiving its optional quantity of gas from the pump 63 as it traverses 50 the tubular chamber 64 into the chamber 60 and thence through the tubular chamber 65 to the throttle valve 66. After passing through the 55 throttle 66 the thoroughly mixed compressed air and gas is conducted through the branch pipe 50 to the port 48 at the receiving end of one of the cylinders, and which port is controlled by the valve 49 before described, while the compressed charge to the other receiving end of the other engine cylinder is conducted through a branch 60 pipe, also indicated at 50.

65 Referring now to the compression of the air utilized in the charge of the engine it will be noted that the piston 9 carried by the narrower band 6 is positioned slightly to the rear of the engine piston 8, this being for the purpose of allowing the piston 8 the proper lead before closing the gates of the engine cylinder prior to receiving the compressed charge within the cylinder 14, and that the gated end of the compression cylinder is provided with a lateral extension 69 in which is housed a suitable check valve 70 and from which extension is provided the pipe connection 71 to one end of the reservoir 51 in one of the brackets 11, while a similar pipe con- 75

nection 72 at the other end of the reservoir leads to a like extension 69 at the gated end of the compression cylinder upon the other side of the engine. While the specific construction of the 5 fuel pump is not a part of my present invention it is deemed essential that such a pump be provided with an adjustable needle valve such as indicated at 74 whereby the discharge of the nozzle 75 may be adjusted to suit requirements 10 for best efficiency. However, the fuel supply pipe to the pump is illustrated at 76 and the piston of the pump at 77, which piston is operated by the rod 78 leading to a suitable eccentric connection 79 to the short shaft 80 operated by the spur gear 81 receiving its power from the larger timing gear 82 fixed to one side of the rotor 5 on the shaft 3. Just outside of the gear 82 and keyed to the shaft 3, is a supporting arm 83 carrying at its extreme outer end the shaft 80. 15 The shaft 3, as before stated, is made adjustable longitudinally of the supporting frame of the engine for example by the screw threaded bolts 84 supported in the brackets 84 carrying the ends of said shaft.

20 In Figure 3 of the drawings there is shown the connection of the T-shaped lever 38 with the track 45 on the rotor 5, this being shown simply as one form of suitable connection. There is also shown in Figure 3 in section the connection 30 of the lever 38 to the track 45 on the rotor 4, and wherein the supporting bracket 101 pivotally carries as at 100 the upstanding rocker arm 102 which is pivotally connected as at 103 to the bracket 38, and which pivotal connection also 35 provides the support for the roller 46 which is in constant engagement with the track 45 of the rotor. See Figure 7 for a better comprehension of this connection.

40 In Figure 5 is illustrated the cooperative relation of the two packing rollers 85 which are carried in the free extremities of the jaws 19 and which form the pivotal connection between the jaws and their respective toggle arms 17 and 18. These rollers impinge the band 45 when closed just prior to the explosion of the charge back of the piston, and may be of any desired construction. However, they are shown as provided with a relatively long bearing portion indicated at 104, and of hollow cylindrical construction having a supporting axial pin 105 extending therethrough and screw threaded into the opposite side of the jaws, leaving a chamber about said pin within the roller for the reception of oil. It is to be understood that these 50 rollers have a bearing substantially wholly thereabouts within the jaw for strength in resisting the impact resulting from repeated explosions of the cylinder charge, as well as insuring lubrication of the roller bearings and their contact with the band, as they rotate independently of the bearing 104. Furthermore in this figure is illustrated a coring out of the cylinder casing as indicated at 86 which may be resorted to for the circulation of water therethrough to cool the cylinders if found necessary. Provision for a similar water space, indicated at 87 and 88, is illustrated in Figure 8 of the drawings, which, obviously, requires an enlargement of the receiving end of the cylinder as more clearly illustrated at 108 in Figure 8 of the drawings; this specific arrangement for cooling purposes, however, forming no part of my present invention.

70 In Figure 4 is illustrated one practical method of piston assembly upon the band 6 which latter may or may not be composed of a single or

double band the latter, however, being illustrated, and the ends of the band sections are shown united within the body portion of the piston. For this union I have illustrated two holding bolts 106 which extend through one-half of the body portion of the piston and through the abutting ends of the band into the other half of the piston and impinging said ends therebetween, while externally of the body portion of the piston is screw threadedly mounted the packing ring carrying annulus 107. However, other forms of uniting the band and formation of the pistons may be resorted to without departing from the spirit of the invention, if so desired.

Any desired form of power take off may be associated with either or both of the engine rotors, and as an illustration of one of such I have shown in Figure 3 of the drawings the shaft 109 carrying the small spur gear 110 meshing with the internally geared annulus 111 fixed to the ro- 20 tor 4.

Having thus described my invention, what I claim and desire to secure by Letters Patent, is:

1. In an engine of the type described having a fuel supply and ignition system associated therewith, two spaced rotors, endless flat bands about said rotors, a pair of spaced relatively long cylinders positioned intermediate of said rotors so that said bands pass axially therethrough, one of said cylinders being a power cylinder and the other a fuel compression cylinder, a plurality of pistons carried by said bands and spaced so that two thereof will cooperatively engage their respective cylinders simultaneously, said fuel compression cylinder and associated pistons providing means whereby compressed charges of combined air and gas are intermittently forced into said power cylinder, means for closing one end of said power cylinder a predetermined time after a piston has entered said cylinder, and means for closing said ignition system to explode said charge in said power cylinder. 30

2. In an internal combustion engine having spaced rotors, fixed power cylinders intermediate of said rotors, an endless flexible band thereabouts for axial travel through said cylinder, spaced pistons on said band, a second endless flexible band about said rotors, spaced pistons on said second band, fixed compression cylinders adjacent said other fixed cylinders for cooperation with said second band and its pistons in compressing and administering an explosive charge to said first mentioned cylinders, and means operable in timed relation with the travel of said pistons for control of closures for one 50 end of all of said cylinders and for ignition of said charge.

3. In an engine of the class described, spaced rotors, endless flat bands about said rotors, spaced pistons carried by said bands, a pair of fixed 60 cylinders so positioned that said bands and pistons traverse same axially, one of said bands and pistons traversing one cylinder for compressing fuel and the other band and pistons traversing the other cylinder for developing 65 power, doors for said cylinders, means for opening the doors to the power cylinder as a piston is about to enter the same and closing the doors immediately after said piston has entered said cylinder, means for admitting a compressed fuel 70 charge from said compression cylinder behind each power piston immediately after it has entered its cylinder and the cylinder doors are closed, and means for igniting said fuel charge and forcing said piston through said cylinder. 75

4. In an engine of the class described, spaced double track rotors having spaced piston receiving notches thereabouts, endless flat bands about said rotors one operable in each track, spaced pistons carried by said bands and engageable in the notches in said rotors to insure unity of operation of said rotors, fixed cylinders so positioned that said bands and pistons traverse same axially, one of said bands and pistons being for compressing the fuel and another of said bands and pistons being for providing power, doors for said cylinders, means for opening the doors of said power cylinder as a piston is about to enter said cylinder and closing same immediately after said piston has entered said cylinder, means for admitting a compressed fuel charge from said fuel compression cylinder behind each power piston immediately after it has entered its cylinder and the doors are closed, and means for igniting said
5. In an internal combustion engine having spaced rotors, fixed power and fuel compression cylinders intermediate of said rotors, an endless flexible band thereabout for axial travel through said power cylinders, spaced power pistons on said band, a second endless flexible band about said rotors, spaced pistons on said second band, said second band and its pistons being for axial travel through said compression cylinders for compressing fuel for said power cylinders and pistons, means for administering an explosive charge from said compression cylinders to said power cylinders, and means operable in timed relation with the travel of said pistons for control of closures for one end of each of said cylinders and for ignition of said charge.

HJALMAR ZAHL
